UNITED STATES PATENT OFFICE

144,635

DESIGN FOR A CAR SEAT END SUPPORT

Peter Schladermundt, Bronxville, and Ladislav L. Rado, New York, N. Y., assignors to Heywood-Wakefield Company, Gardner, Mass., a corporation of Massachusetts

Application February 6, 1946, Serial No. 126,308

Term of patent 7 years

(Cl. D15—8)

To all whom it may concern:

Be it known that we, Peter Schladermundt and Ladislav L. Rado, citizens of the United States, residing respectively at Bronxville, in the county of Westchester, and at New York, in the county of New York, both in the State of New York, have invented a new, original, and ornamental Design for Car Seat End Support, of which the following is a specification, reference being had to the accompanying drawing, forming part thereof.

Figure 1 is a side perspective view of a car seat

end support showing our new design, the opposite side thereof being plain; and

Figure 2 is a rear elevational view of the same.

This application is a continuation-in-part of our copending application, Serial No. D-119,375, filed May 3, 1945, for car seat.

We claim:

The ornamental design for a car seat end support, as shown and described.

PETER SCHLADERMUNDT,
LADISLAV L. RADO.
